UNITED STATES PATENT OFFICE.

NAT HARRIS FREEMAN, OF HOLBORN, LONDON, ENGLAND.

CARBONIZING OR DISTILLATION APPARATUS.

Application filed February 3, 1921. Serial No. 442,196.

To all whom it may concern:

Be it known that I, NAT HARRIS FREEMAN, a citizen of the United States of America, residing at Holborn, London, England, have invented certain new and useful Improvements in Carbonizing or Distillation Apparatus (for which on February 12, 1918, I filed an application for patent in England), of which the following is a specification.

This invention relates to carbonizing or distillation apparatus of the kind in which the material under treatment is passed in a zig-zag manner through a series of superposed compartments by means of stirrers or scrapers and in which each compartment is heated separately in a controllable manner. The present invention has for one of its objects to improve and render more efficient and reliable apparatus of this kind, and to provide for more regular and definite products being obtained. In a known circular retort of a kind other than the foregoing and consisting of a chamber provided with a number of plates placed above each other and mounted alternately on a central revolving shaft and on the casing, the material admitted on to the uppermost revolving plate is gradually scraped therefrom by scrapers or deflecting plates hinged to the cover of the chamber and allowed to fall on to the next lower fixed plate from which is scraped or deflected by scrapers attached to the lower side of the revolving plate and permitted to fall on to the next lower revolving plate and so on through the chamber.

According to the present invention each successive carbonizing or distilling chamber is provided with a centrally disposed rotary platform for receiving coal or like material, over which platform the material when entering the chamber is caused to move in one direction by stationary shoes or deflectors, whilst similar shoes or deflectors carried by the platform on the opposite side feed the material in the reverse direction to the outlet of said chamber, said chambers being so constructed and arranged as to afford an independent annular heating chamber between each pair of adjoining carbonizing chambers and means being provided to enable the gaseous products of distillation to be conducted away separately from each chamber.

In order that the invention may be clearly understood and readily carried into effect

it will now be more fully described with the aid of the accompanying drawings, in which:

Figure 1 is a vertical (fragmentary) section of the improved apparatus; 60

Figure 2 is a sectional plan on line $x-x$ of Figure 1, and showing in dotted lines the relative position of certain of the shoes;

Figure 3 is a sectional plan on line $y-y$ of Figure 1; 65

Figure 4 is a vertical sectional view through the members e and d ;

Figure 4^a is a fragmentary horizontal section taken just above the member d ; 70

Figure 5 is a vertical section through the member e , e' ;

Figure 5^a is a fragmentary horizontal section taken just above the member e ; 75

Figure 6 is a diagrammatic side elevation, partly in section, showing one form of temperature controlling means applied to a heating chamber a , and

Figure 7 is a vertical section, enlarged, showing a detail of the apparatus shown in Figure 6. 80

Like letters of reference indicate like parts throughout the drawings.

$a-a$ are the chambers, of which there may be any number, preferably arranged in tiers, the coal or like material being fed into the apparatus through an opening b at the top and caused to pass around and through each chamber a . From the first or upper chamber the coal enters the second chamber at 85 a point central thereto and after having moved towards the periphery of said second chamber and back again to the centre enters the next or third chamber and so on through the several chambers. The chambers a , a are disposed concentric to a vertical shaft c adapted to be rotated by means of a pulley c_1 , whilst within each chamber is provided 90

a series of blades, vanes or shoes d , d carried by a rotary platform e (Figures 1 and 4) keyed to the shaft c for directing and conducting the coal during its passage through each chamber. Said shoes d , d of which there may be any suitable number arranged 95 in any appropriate manner when rotated within the chamber agitate and feed the coal from one chamber to another to permit of the by-products being separated therefrom. In addition to the rotating or revolving shoes, 100

fixed shoes e^1 , e^1 (Figures 1 to 5) are provided to deflect the coal and cause it to fall 105 over the edges of the rotary platform e and 110

in the latter connection the rotary platform or table *e* will also carry the coal into contact with the shoes *e*¹, *e*¹, said platform being designed to effect the feeding of the 5 coal in the desired direction and at the required rate. Each chamber is provided with an outlet or outlets *f*, *f* whereby the distillation products separated during the passage of the coal through each chamber 10 may be drawn off. Between each adjoining pair of chambers *a*, *a* annular chambers *a*¹ are afforded into which gaseous fuel burners *g* may be inserted to permit of the heating of each chamber *a* in such a manner that the 15 temperatures of each chamber may be regulated as required.

Any convenient construction of means for controlling the temperature may be used. For example, it may be of the type in which 20 a body of mercury is caused to close an electrical circuit for actuating means to reduce the temperature, such as that described and shown in my co-pending application, Serial No. 442,195. This construction is 25 shown in Figures 6 and 7. Referring to these figures, the mercury container, which is outside the heating chamber *a*, consists of a tubular part 2 in an upright fixed portion 3, the upper part of which tubular part 30 is connected to the end of a tube 4 communicating with the air vessel 5 (which is within the heating chamber *a*) and a movable tubular part 6 of glass or other electrical insulating material. On end of this 35 movable part 6 is secured in a metal trunnion 7 in the fixed portion 3 and communicates through passages 8, 9, 10 and 11 in the trunnion 7 with the lower end of the tubular part 2 of the mercury container. As 40 shown in Figure 7, the trunnion is in the form of a retort plug having in its periphery an annular groove 8 into which the lower end of the part 2 opens in all positions into which the trunnion may be 45 turned. A radial passage 9 connects the groove 8 with the inner end of an axial bore-hole 10 in the trunnion, and the part 6 opens at the outer end of the trunnion into the other end of the bore-hole by way 50 of a second radial passage, as shown at 11. The trunnion 7 is slightly conical and ground into its bearing in the part 3 and secured therein by a screw nut after the manner of a plug cock. The angularly adjustable parts are shown in an inclined position in Figure 6, and directed vertically 55 downwards in Figure 7. It will be seen that the trunnion 7 constitutes an adjustable connecting part between the container 2 and the tube 6. Within the part of the adjustable part 6 of the mercury container above 60 the mercury 12 therein, an electrical terminal 13 in the electrical operating circuit is axially arranged, the said terminal being the end of a wire which passes out of the

upper end of the said adjustable part 6 and is bent around and secured to a rod 14 which is slidably secured in a carrier 15 working on a carrier rod 16 parallel to the said adjustable part. The end of the carrier rod 16 70 contiguous to the trunnion 7 is secured in a metal plate 17 which is carried by the said trunnion through the medium of a block of electrical insulating material 18 secured thereto. The said metal plate 17 also carries a screw 19 with hand wheel 20, which screw is engaged with a screw thread in the carrier 15. By turning this screw the position of the carrier 15 and consequently the position of the electrical terminal 13 in the mercury container may be very finely adjusted, a coarse adjustment being made by sliding the rod 14, to which the outer end of the terminal wire or conductor 13 is secured, in the carrier 15 in which it is retained after adjustment by a clamping set screw, not shown. The fixed portion 2 of the mercury container is in the aforesaid electrical circuit and electrical current 80 passes through it to the mercury when the 85 circuit is closed. The adjustable part 6 of the mercury container with the other parts carried by the trunnion 7 may be moved around by hand in an arc from a vertical 90 to a horizontal or nearly horizontal position, the parts remaining in their adjusted position by the friction of the trunnion 7 in its bearing. The electrical circuit is 95 through the part 2, trunnion 7, and mercury 100 12 to the terminal 13, when in contact with the mercury, rod 14, carrier 15, carrier rod 16, and plate 17. In the circuit is a battery 21 and electro-magnet 22, which, when the 105 circuit is closed by the mercury 12 contacting 110 with the terminal 13, is energized and operates the pivoted armature 23. This armature 23 has on it two metal pins 24 located and working in two mercury cups 25 which are in another electrical circuit comprising a battery 26 and electro-magnet 27. 115 When the armature 23 is actuated the pins 24 are depressed into contact with the mercury in the cups 25 and close the second electrical circuit, thereby energizing the electro-magnet 27 which actuates a pivoted 120 armature 28 carrying a valve or damper 29 which is situated adjacently to the mouth of the gas supply pipe 30 to the burner *g* so that as the armature 28 is actuated the valve or 125 damper 29 closes or opens the gas supply pipe 30 more or less. The mouth of the gas supply pipe 30 and the armature 28 are located in a chamber 31 to which the fuel is supplied. When, therefore, the mercury 130 12 is caused to rise in the part 6 of the mercury container, by the expansion of the air in the vessel 5 due to rise of temperature in the heating chamber, until the mercury contacts with the terminal 13, the first electrical circuit is closed, thereby closing the sec- 135

ond circuit and operating the damper 29 to reduce the fuel supply to the burner 9.

In order to allow attainment of the desired temperature in the first instance an adjustable relief valve 32 is provided in the pipe 4, which valve is opened or allowed to open while the said temperature is being attained and when the said temperature is reached the said valve is closed, the purpose being to prevent undue pressure in the air vessel 5.

By turning the trunnion 7 and parts carried by it more and more to the vertical from the horizontal the surface of the mercury 12 in the parts 6 becomes greater and greater and the distance the mercury travels under a given increase of pressure is increased, the result being a very accurately acting adjustment of the control.

It will be seen that with temperature control means of this character the temperature in each chamber may be regulated as required by adjusting the movable part 6 to the desired angular position.

It will, of course, be understood that the number of chambers may be varied as required according to the nature of the material passing through or being treated in the apparatus. The chambers in series may be employed in conjunction with coke retorts or any other distillation plant, it of course being understood that the temperature in each of the separate chambers or compartments referred to will be maintained according to the heat required to effect one or other stage of the distilling or carbonizing process.

What I claim as my invention and desire to secure by Letters Patent is:—

A distillation apparatus for coal or other similar material, comprising a casing, partitions in said casing dividing the interior thereof into a series of superposed compartments, conduits situated centrally of the casing and extending between adjacent compartments and independent annular heating chamber for each compartment, means for controlling the heat supply to said heating chambers in such a manner that the temperature in each heating chamber is maintained constant and the temperature of successive heating chambers is different, means for conducting the distillate separately away from each compartment, a platform in each compartment, means for rotating said platforms, means for feeding the material to be distilled on to the platform in the uppermost compartment towards the centre of said platform, means for conducting away the residue from the lowermost compartment, means for causing the material to traverse the platforms from the centre outwards during their rotation and to deliver the material over the outer edge of each platform on to the outer portions of the floor of the compartment to which it is appropriated, and means for traversing the material across the floor of said compartment inwards towards the conduit leading into the next lower compartment.

In testimony whereof I affix my signature.

NAT HARRIS FREEMAN.
